Primary Examiner—Ruth McInroy

(57) **CLAIM**

I claim the ornamental design for body of vacuum cleaner,
as shown and described.

DESCRIPTION

FIG. 1 is a perspective view of body of vacuum cleaner
showing the new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is a front view thereof, the portions shown in broken
lines are for illustrative purposes only and form no part of
the claimed design; and,

FIG. 9 is a front view thereof showing the device in use, the
portions shown in broken lines are for illustrative purposes
only and form no part of the claimed design.
